United States Patent Office

Des. 213,615
Patented Mar. 25, 1969

213,615

AUTOMOBILE BODY

Thomas L. Tyrrell, 6424 N. 40th St.,
Milwaukee, Wis. 53209

Filed Mar. 4, 1968, Ser. No. 10,849

Term of patent 7 years

Int. Cl. D12—08

U.S. Cl. D14—3

Fig. 1

Fig. 2

Fig. 3

Fig. 5

Fig. 6

FIGURE 1 is a perspective view illustrating the front and left side of the automobile body of the present invention;

FIGURE 2 is a perspective view illustrating the rear and left side thereof;

FIGURE 3 is a view in front elevation thereof;

FIGURE 4 is a view in left side elevation thereof;

FIGURE 5 is a plan view thereof; and

FIGURE 6 is a view in rear elevation thereof.

The side opposite that shown in FIG. 4 is a mirror image thereof.

The elements shown in broken lines are included only for illustrative purposes.

I claim:

The ornamental design for an automobile body, as shown and described.
